UNITED STATES PATENT OFFICE.

LOUIS J. REMMEL, OF NEWARK, NEW JERSEY, ASSIGNEE TO AMELIA M. MAIER, OF NEWARK, NEW JERSEY.

MACHINE FOR FILLING ROTARY BROOMS.

Application filed January 5, 1922. Serial No. 527,220.

To all whom it may concern:

Be it known that I, LOUIS J. REMMEL, a citizen of the United States, and a resident of Newark, county of Essex, and State of New Jersey, have invented certain new and useful Improvements in Machines for Filling Rotary Brooms, of which the following is a specification.

This invention relates to a machine for filling rotary brooms or brushes, and is particularly adapted for filling the brush frames that are used in snow sweepers and for similarly heavy purposes, into which frames reeds, which form the brush material, are placed in folded position.

In brushes of this kind reeds are folded over at approximately the center, and the folded ends are secured in the brush frame and the free ends are used for brushing or sweeping, this being well illustrated and described in my Patent No. 1,309,695, issued July 15, 1919. After the folded reeds are placed in the frame a bar is slid across the frame to hold the folded ends of the reeds in position, these reeds being grouped rotatively and also longitudinally along the brush frame.

It has heretofore been a slow process to fill these brooms by hand, which is disadvantageous, particularly in times of heavy snows when rapid replacement of the brush material in the same frame is essential in order to keep pace with the requirements incidental to keeping railways and the like free from snow.

The object of this invention is to provide a machine in which the brush material is supplied in its straightened condition, in the form of reeds or rattan, and the brush frame is mounted on a carriage, and when the machine is operated the brush material is folded over and at the same time the brush frame is brought forward and embraces the folded end of the material, so that all that it is necessary to do is to place a rod across the frame and fasten it in position so as to confine the folded reeds in the frame.

When the folding means and the carriage are returned to normal position, to enable a supply of reeds for the next row on the broom to be placed in the machine I have devised an automatic means for partially rotating the brush frame so that the next vacant space for brush material is made available for the next operation of the ma-

chine, so that this step-by-step movement of the brush frame enables the reed-receiving portions of the frame to be successively filled, and the operator's function is simply at each operation of the machine to see that the proper quantity of brush material is placed therein.

The invention further consists in certain details of construction to be hereinafter more fully described and finally embodied in the claims.

A machine embodying my invention is illustrated in the accompanying drawing, in which Figure 1, Figure 2, Figure 3 and Figure 4 are perspective views of the machine showing various positions its parts occupy in the operation of the device. Figure 5 is a detail perspective of part of the positioning means for the brush material, and Figure 6 is a detail section of part of the positioning means. Figure 7 is a detail perspective of the locking means for the clamping plate. Figure 8 is an enlarged sectional detail of the clamp shown in Figure 7. Figure 9 is a detail perspective of the jaws that cooperate to hold the clamping plate down. Figure 10 is a detail section of one of the prongs on the table for separating the brush material. Figure 11 is a detail view of the form of step-by-step movement illustrated as the means for moving the brush frame rotatably. Figure 12 is a front view of the device shown in Figure 11. Figure 13 is a detail view showing the brush frame, the brush material being shown in dotted outline, and Figure 14, Figure 15, Figure 16, Figure 17 and Figure 18 are longitudinal sectional views through the machine to illustrate the successive positions assumed by the parts of the machine in completing the operation thereof.

The machine, for the purpose of ease of operation, is usually built up on supports or legs 10, on which legs is arranged the table 11 which is adapted to cooperate with the folding plate 12 for folding the brush material 13, which is in the form of reeds, these being substantially stiff and normally straight, and I provide a guard board 14, against which the ends of the brush material are placed so as to make the ends substantially even. These reeds, which provide the brush material, are arranged in groups, for the purpose of which I provide teeth 15 which are arranged on the table 11, and

similar teeth 16 are arranged to separate the groups where the reeds rest on the clamping plate 12, this being clearly evident from Figures 1 and 14.

To still further hold the reeds in alignment at a point closer to the place of bending, I arrange the teeth 17, these being aligned with the teeth 15 and 16, but these teeth 17 are cleared away from the path of the folding plate and are thus not jammed in the folded reeds by a mechanism to be described hereinafter.

The folding plate is operated by any suitable means, but I prefer the mechanism shown, which comprises an internal segmental gear 18 on each side of the table, on which segmental gear the folding plate 12 is fastened, as will be seen from Figures 2 and 14, the internal teeth 19 of the gear being in mesh with the smaller gear 20, and for the purpose of ease of operation by hand the gear 20 is arranged on the same shaft with the gear 21, which, in turn, is operated from the small gear 22 to which the crank handle 23 is secured.

It will thus be evident that as the crank handle 23 is turned, the train of gearing will cause the segmental gears 18 to rotate on their bearing shafts 24.

Previous to this bending operation I prefer to use a clamping plate 25 which is pivoted, as at 26, on each side of the guide board 14 and can be freely swung when not locked in position, the clamping plate 25 having downwardly projecting teeth substantially in register with the teeth 15, 16 and 17, this clamping plate having dogs 27, as will be seen from Figure 14, and the ends of which are shown in Figure 7.

In order to lock this locking plate down in position to hold the brush material while it is being folded, I prefer the locking means shown in detail in Figure 7, which includes the shaft 28 having the dogs 29, the shaft 28 being rotatable and the dogs being secured to the shaft so that they rotate with it, and a link 30 is fastened by a short lever 31 to the shaft 29, and a link 32 on the shaft 33, which is operable by means of the handle 34, permits a partial turning of the shaft 33, which pulls down the link 30, swings the dogs 29 against the dogs 27, and the locking plate is thus pulled down to lock the locking plate in position.

It is released preferably automatically by reason of the rod 35 which projects up through the machine, as will be seen in Figures 2 and 14, and is engaged by the folding plate 12 when it completes its folding operation, and when thus pushed down it actuates the mechanism above described to swing the shaft 28 and its dogs 29 so that the dogs 27 are released.

At the rear of the machine is arranged a carriage which is movable toward and from

the folding means and includes means for supporting the frame of the brush. The illustration shows tracks 36 which extend to the rear of the table, and the carriage includes slides 37 which are connected by a rod 38 which is rotatable and forms the support for the brush frame 39. The brush frame, comprising end plates 40 and intermediate plates 41 which are connected by bars 42 between which the folded bunches of brush material are placed, is held in position by bolts 43, shown in Figure 13. The brush frames are usually made up of two semi-circular members, and one member is filled at a time. A connection between the carriage and the folding means is indicated by the rods 44 connected by the link 45 to the end of the folding plate 12, so that when the folding is carried out the brush frame is advanced to embrace the folded end of the material, as shown in Figure 18.

To take up any irregularities in the folded end of the brush material when necessary, and to provide for a jamming of the brush frame over said material, I provide a supplemental carriage sliding means which comprises a handle 46, which is shown in Figures 2, 3 and 18, which is extensible so as to be projected from the link 45 and acts as a lever therefor when in use, and which can be arranged to be folded out of the way by reason of its being pivoted, as at 47. When the brush frame has been firmly seated over the looped end of the brush material, the rod or long bolt 43 (Figure 13) is slid lengthwise through the brush frame and then fastened and the brush knots are in place.

While these above described operations have been taking place, the brush frame is held against rotation by reason of its weight being resisted by a pawl 48 secured to one of the slides 37. The brush frames are filled by successively filling the compartments or recesses, beginning at the top one, and then bringing them successively into position by raising the frame the required distance on its rearward movement.

One form of mechanism for performing this function comprises the rod 49 loosely swinging on the shaft 38 and loosely fitting in the space between the studs 50 of the plate 51. The rod 49 carries a pawl 52 which is adapted to engage the notches 53 in the plate 54, which is the element engaged by the pawl 48 and which is secured to the shaft 38. The notches are spaced to swing the brush frame a distance equal to the space between the brush material recesses or compartments, which are separated by the bars 42.

When the carriage travels forward, the rod 49 is swung to bring its pawl into the next lowest notch 53, and when the carriage

is retreated, the rod pushes the pawl 52, and consequently the plate 54, the shaft 38 and the brush frame, around so as to raise the next empty compartment in alignment 5 with the folding means. The reversal of the machine is brought about by a reverse operation of the handle 23.

To permit a quick and easy grouping of the reeds when they are placed on the table 10 before they are folded, that is, in the position shown in Figures 1 and 14, I prefer to place the set of teeth 17 which project above the tops of the other teeth, as will be seen from Figure 2, these being illustrated more in detail in Figure 5, and they are fastened to a rotating shaft 55 having a short arm 56 thereon, which is connected to a curved lever 57, as seen from Figures 14-17, inclusive, which is pivoted at 58 to a post 59 and pivoted at 60 to a short lever 61 which is engaged by a lip 62 on a long lever 63 pivoted at 64 and extending back and connected up, as at 65, to the link 66 which is connected to an arm 67 fixed to the rod 44 on one side of the 25 machine.

The duty of this structure is to move these teeth out of the way before the folding is completed, and this is accomplished as shown in Figure 17, the swinging of the arm 44 pulling up on the link 63 so as to raise the rear end of the long lever 63, which pushes down on the short lever 61 by reason of the lip 62, which breaks the joint at 60, thus swinging the teeth 17 out of the way, as shown in Figure 17. This device is reset before the next set of reeds is installed, by pulling up on the short lever 61.

In the folding, the groups are held in substantial alignment, first by reason of the partition plates 68 shown in detail in Figure 6, and also seen in the right hand part of Figure 2, which partition plates extend beyond the teeth 69 which are arranged on the free end of the clamping plate 25. These teeth 45 69 are fastened in a suitable strip 70 on the end of the clamping plate.

In the folding, the rear ends of the reeds are held in the required groups by the teeth 71 fastened to the edge of the folding plate 50 12 and illustrated particularly in Figure 10, being held down by bolts 72 passing through the plate 73 which fastens the teeth, by reason of their right-angled parts 74, to said folding plate.

It will be evident that when a brush frame comprising one member or one-half of a complete rotary broom is filled, it is removed and another one inserted, and after these 55 two are filled the two halves are connected together by suitable means, the form shown comprising eyes 75, as will be seen from Figure 3.

It will be evident that the exact form of brush frame illustrated is not essential, as 60 65 the machine is applicable to different forms

of brush members, and details of construction can be altered without departing from the scope of the invention.

I claim:

1. A machine for filling rotary brushes 70 comprising a means for holding and folding brush material, means for holding a brush frame, and means for placing said frame over the folded material, the folding means being substantially as wide as the frame so 75 that the frame is filled for its full width when it is placed over the brush material.

2. A machine for filling rotary brooms comprising a means for holding and simultaneously folding groups of brush material, 80 a carriage to move a brush frame to and from the folding means whereby the frame can be filled for its width with said groups of brush material, and means for rotating the frame step-by-step.

3. A machine for filling rotary brooms comprising a means for folding brush material, a carriage to move a brush frame to and from the folding means, means for locking the brush frame against rotation when 90 it receives the folded material, and means for rotating the brush frame step-by-step when it is removed from the folding means.

4. A machine for filling rotary brooms comprising a means for holding and folding separated groups of brush material, means 95 for supporting and rotating in a step-by-step movement a brush frame, and means for automatically advancing said brush holding means to receive the brush material when folded.

5. A machine for filling rotary brooms comprising a means for holding and folding brush material, a carriage operated from the folding means, said carriage including means for holding a brush frame, and means for 105 rotatably moving the brush frame when it is removed from the folding means.

6. A machine for filling rotary brooms comprising a foldable support for brush material, means for clamping brush material in the support, means for folding the support, and a carriage for holding a brush frame, said carriage being movable to bring the frame in position to receive the folded end 110 of the material.

7. A machine for filling rotary brooms comprising a table on which brush material is adapted to be laid, a folding plate in which one end of the brush material bears, means for swinging the plate so as to fold the material, a locking plate to hold the material in folding, and means for supporting a brush frame and for carrying said brush frame over the folded end of the material. 120

8. A machine for filling rotary brooms comprising a table on which brush material is adapted to be laid, a folding plate in which one end of the brush material bears, means 125 for swinging the plate so as to fold the ma-

terial, a locking plate to hold the material in folding, a carriage for holding a brush frame, said carriage including means for rotatably moving the brush frame when it is removed from the brush material, and means for sliding the carriage so that the brush frame embraces the folded end of the material.

9. A machine for filling rotary brooms comprising a table, a folding plate hinged to the table, the table and plate forming a supporting and folding means for brush material, mechanism for swinging the plate to fold the material, a carriage for supporting a brush frame, and a connection between the plate and carriage to slide the carriage.

10. A machine for filling rotary brooms comprising a table, a folding plate hinged to the table, the table and plate forming a supporting and folding means for brush material, mechanism for swinging the plate to fold the material, a carriage for supporting the brush frame, a connection between the plate and carriage to slide the carriage, a brush carrying means on the carriage, and mechanism for rotatably moving the brush when the carriage is slid.

11. A machine for filling rotary brooms comprising a table, a folding plate hinged to the table, the table and plate forming a supporting and folding means for brush material, mechanism for swinging the plate to fold the material, a carriage for supporting a brush frame, a connection between the plate and carriage to slide the carriage, a rotatable brush carrying means on the carriage, and a step-by-step movement imparting means for actuating the brush when the carriage is moved.

12. A machine for filling rotary brooms comprising a table, a folding plate hinged to the table, the table and plate forming a supporting and folding means for brush material, a locking plate for holding the material down during the folding, means for holding the locking plate in its holding position, and a releasing means for said locking plate and disposed so as to be operated by the folding plate when the folding of the material has been completed.

13. A machine for filling rotary brooms comprising a table, a folding plate hinged to the table, the table and plate forming a supporting and folding means for brush material, a segmental gear to which the folding plate is attached, means for rotating the gear, a carriage having means thereon for supporting a brush frame, a connection between the carriage and the folding plate so that the brush frame is advanced when the material is folded and at the completion of the folding embraces the folded end of the

material, and a step-by-step mechanism for rotatably moving the brush frame by the sliding of the carriage.

65

14. A machine for filling rotary brooms comprising a table, a folding plate hinged to the table, the table and plate forming a supporting and folding means for brush material, a segmental gear to which the folding plate is attached, means for rotating the gear, a carriage having means thereon for supporting a brush frame, a connection between the carriage and the folding plate so that the brush frame is advanced when the material is folded and at the completion of the folding embraces the folded end of the material, a step-by-step mechanism for rotatably moving the brush frame by the sliding of the carriage, a locking plate adapted to hold the brush material in position while it is being folded, and a release for said locking plate, which release is actuated by the folding plate when the folding is completed.

70

15. A machine for filling rotary brushes comprising a means for holding and folding brush material, a means for supporting a brush frame, and mechanism for forcing said frame over the folded end of the brush material.

75

16. A machine for filling rotary brushes comprising a means for holding and folding brush material, means for supporting a street sweeper brush frame, the brush material being folded for a space substantially as wide as the frame, and means for forcing the frame over the folded end of the brush material, whereby at each forcing the frame is filled for its entire width.

80

17. A machine for filling rotary brushes whose frames have aligned brush-receiving spaces, comprising a folding means for brush material to present said folded material to said spaces, and means for holding a brush frame and for advancing it to force the frame so that its spaces receive the folded brush material, whereby the spaces are filled simultaneously.

85

18. A machine for filling rotary brushes whose frames have aligned brush-receiving spaces, comprising a folding means for brush material to present said folded material to said spaces, means for holding a brush frame and for advancing it to force the frame so that its spaces receive the folded brush material, whereby the spaces are filled simultaneously, and means for imparting a step-by-step rotary movement to the frame when it is removed from the folding means.

90

In testimony that I claim the foregoing, I have hereto set my hand, this 29th day of December, 1921.

105

LOUIS J. REMMELE.
